NURSING BOTTLE HOLDER

Filed Feb. 27, 1931

Carl S. Ashby,
INVENTOR

Leona Taylor
WITNESS:

G. L. Evans
ATTORNEY

UNITED STATES PATENT OFFICE

CARL S. ASHBY, OF CLEVELAND, OHIO

NURSING BOTTLE HOLDER

Application filed February 27, 1931. Serial No. 518,844.

This invention relates to nursing bottle holders, and its general object is to provide a bottle holder that is formed from strands of wire and will support a bottle in nursing position in a manner whereby the bottle will be flexibly held so that movement of the child will cause correspondent movement of the bottle, with the result the bottle cannot be casually moved out of reach of the child.

A further object of the invention is to provide a nursing bottle holder that is simple in construction, inexpensive to manufacture, exceptionally convenient to use and efficient in operation and service.

This invention also consists in certain other features of construction, and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a side elevation illustrating my holder and having a bottle supported thereby.

Figure 2 is a rear view thereof.

Figure 3 is a fragmentary side elevation showing the bottle receiving means supported in a position when not in use.

Figure 4 is a sectional view taken approximately on line 4—4 of Figure 3, looking in the direction of the arrows.

Figure 5 is a top plan view of the holder.

Referring to the drawings in detail, the reference numeral 1 indicates the supporting portion of the device and which is formed from a single strand of wire having a base 2 which is substantially semi-circular in formation and from the ends of the base 2 the strand of wire is extended upwardly in semi-circular formation to provide the upright portion 3.

One of the upper ends of the upright portion is looped upon itself to provide a ring 4 and thence is twisted about the opposite end to provide what may be termed a substantially L-shape twisted portion 5. From

the twisted portion 5, the first mentioned end is directed downwardly and terminates in an elongated loop 6 which cooperates with the ring 4, for a purpose which will be presently apparent, while the other end terminates in a hook 7 directed substantially at right angles to the loop 6.

The supporting portion of the device is substantially U-shape in configuration, and is also formed from a single strand of wire in a manner to provide a hanger portion 8 having formed with one end an enlarged ring 9 and at its opposite end the hanger portion 8 is disposed downwardly and terminates in a relatively small ring 10.

The rings 9 and 10 are adapted to receive the bottle which is indicated by the letter A in a manner whereby the body portion of the bottle is received by the enlarged ring 9, while the neck of the bottle is received by the ring 10 to hold the bottle in a position as clearly shown in Figure 1 of the drawings, as it will be noted that the hanger portion 8 is received by the ring 4 and the loop 6 and is freely swingable in the ring 4 and loop 6 as well as movable longitudinally therein, with the result the bottle cannot be casually moved out of reach of the child while nursing as will be apparent.

When the bottle holding portion is not in use, it is swung to a position as shown in Figure 3, and the depending portion of the hanger is received by the hook 7 as clearly shown in Figure 3.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:

1. A nursing bottle holder comprising a supporting portion including right angled disposed integrally connected members, one of said members having their ends twisted about each other, a holder portion, bottle receiving means formed with said holder portion, means formed adjacent the twisted por-

tion to receive the holder portion for rotatable and longitudinal movement, and a hook for holding the holder portion in inoperative position.

2. A nursing bottle holder comprising a supporting portion including a base, an upright portion formed with said base and having its upper ends twisted about each other, one of said ends being looped to provide a ring, and terminating in a loop arranged parallel with the ring, a hook formed with the other end, a bottle holder portion including a hanger received by the loop and ring for rotatable and longitudinal movement, bottle receiving means formed with the bottle holder portion and said hook being adapted to receive the bottle holder portion for securing the latter in inoperative position.
3. A nursing bottle holder comprising a supporting portion including a base, an upright portion formed with the supporting portion and being substantially semi-circular in formation, one of the ends of the upright portion having formed therewith a ring, and terminating in a loop arranged parallel with the ring, a hook formed with the other end, a bottle holder portion including a hanger loosely received by the ring and loop, a relatively small ring formed with the bottle holder portion and disposed at one end thereof, an enlarged ring at the opposite end, said last mentioned rings being adapted to receive a bottle to support the latter in nursing position, and said hook being adapted to secure the bottle holder portion in inoperative position.
4. A nursing bottle holder comprising a supporting portion including a base of semi-circular formation, an upright portion of semi-circular formation and being formed with a base, the upper ends of said upright portion being twisted about themselves to provide an L-shape portion, one of said upper ends being provided with a ring and a loop arranged in parallelism with each other, a hook formed with the opposite end and being disposed at right angles with respect to the loop, a bottle holder portion including a hanger mounted for rotatable and longitudinal movement in the ring and loop, a depending portion formed with the hanger and terminating in a relatively small ring, an enlarged ring formed with the hanger and cooperating with the relative small ring for supporting a bottle in nursing position, and said hook being adapted to receive the depending portion to hold the bottle holding portion in inoperative position.

In testimony whereof I affix my signature.
CARL S. ASHBY.
